UNITED STATES PATENT OFFICE.

F. S. MERRITT, OF NEW YORK, N. Y.

COOKING-RANGE.

Specification of Letters Patent No. 34,212, dated January 21, 1862.

To all whom it may concern:

Be it known that I, F. S. MERRITT, of the city, county, and State of New York, have invented a new and useful Improvement in Cooking-Ranges; and I do hereby declare that the following is a full, clear, and exact description of the same, reference being had to the accompanying drawings, making a part of this specification, in which—
10 Figure 1, is a vertical section of a cooking range with my invention applied to it taken in the line x, x , Fig. 2. Fig. 2, a horizontal section of the same taken in the line y, y , Fig. 2. Fig. 3, a detached vertical section of my invention taken in the line z, z , Fig. 2. Fig. 4, a vertical section of one side of the range taken in the line a', a' , Fig. 1. Figs. 5, and 6, are horizontal sections of a portion of the invention taken respectively in 15 the lines $b' b' c' c'$ Fig. 1.
20 Similar letters of reference indicate corresponding parts in the several figures.

This invention consists in arranging in the back part of the fire-chamber of a cooking range a rotating cylinder or frustum of a cone, one portion or side of which is of fire brick or other equivalent substance or material and the opposite portion or side forming a water-back, an air heating chamber being between the fire-brick and water-back; whereby either the fire-brick or water back may be made to form the back of the fire-chamber as may be desired, and an air heating chamber obtained which may be 30 constantly used or in other words, used in either of the two portions of the cylinder or frustum of a cone.

The invention also consists of a peculiar means employed for operating the cylinder or frustum of a cone as well as a novel arrangement for automatically supplying the water-back with a flow of water and cutting off the same as hereinafter described.

To enable those skilled in the art to 45 fully understand and construct my invention I will proceed to describe it.

A, represents the fire-chamber of a cooking range which may be constructed and arranged in any proper way and lined at its 50 sides with fire-brick B, as usual.

The fire-brick C, which at certain times forms the back of the fire-chamber is of convex form and is a vertical portion of a frustum of a cone D, as shown clearly in 55 Figs. 1 and 2. The opposite portion of D, is hollow constructed of sheet-metal and

forms a water-back E, shown clearly in Figs. 1 and 2.

F, is a chamber between the fire-brick C, and water-back E. This chamber has openings a , at its top and bottom for the air to lower part of a compartment G, at the back of the fire-chamber and the heated air passing out through the upper part of said chamber as indicated by the arrows 1. 60 65

The frustum D, works on trunnions $a^x a^x$ which are tubular and communicate with the water-back E. The trunnions a^x , externally are of conical form and are fitted in sockets $b^x b^x$, which have tubes c, c' respectively attached to them. Such trunnion a^x , has two passages $d d'$ made laterally in it at right angles and the sockets $b^x b^{xx}$, have similar openings or passages e, e' the passages e , communicating with the tubes c, c' . 70 75 The frustum D, has vertical pins f , attached to its bottom said pins being in a curved line concentric with the bottom. These pins f , gear into a screw H, which is on a rod I, that passes obliquely through 80 the range at one side, said rod I, having a crank g, on its front end—at one side of the frustum D, there are attached two cleats or ribs h, h, which serve as stops.

The operation is as follows: The operator or attendant by turning the rod I, may turn the frustum D, so that either the fire-brick C, or water-back E, may form the back of the fire-chamber A. When the water-back E, forms the back of the fire-chamber there is a flow of water upward through the water-back as indicated by arrows 2, as the tubes c, c' are in line with the holes e' of the sockets b^x, b^{xx} , and the holes e' , are in line with the holes or passages $d', 90$ 95 in the trunnions a^x ; when however the frustum D, is turned so that the fire-back C, forms the back of the fire-chamber, the passages d , in the trunnions are in line with the holes or openings e , in the sockets b^x, b^{xx} , and the water escapes from the water-back through the opening e , in the lower socket b^{xx} , as indicated by arrows 3, Fig. 6. 100

Thus it will be seen that the flow of water through the water-back E, is stopped and 105 started automatically. The air heating chamber F, not only heats air for warming other apartments than that in which the range is placed but also serves to isolate the water-back from the fire, when the former 110 is turned out from the latter and the fire-brick forms the back of the fire-chamber.

The invention is extremely simple and efficient and is attended with a trifling expense in construction.

Having thus described my invention what I claim as new and desire to secure by Letters Patent; is.

1. The combination of a fire-brick C, and water-back E, arranged at the back part of the fire-chamber A, of a cooking range so as to form a cylinder or a frustum of a cone and be rotated so that either the fire-brick or the water-back may form the back of the fire-chamber as desired.

2. The air heating chamber F, interposed between the fire-brick C, and water-back E, when the same are suspended and made to rotate as and for the purpose specified.

3. The tubular trunnions a^x , provided

with passages d, d' in combination with the sockets b^x , b^{xx} , provided with the holes or openings e, e, and arranged and applied to the rotating water back E, as shown to automatically stop and start the flow of water through the water back E, as set forth.

4. Rotating the frustum D by means of the pins or teeth f, and screw H, when the latter is placed or formed on a rod I, which passes through the range at one side of the fire-chamber so that the frustum can be turned by the operator or attendant at the front of the stove.
